UNITED STATES PATENT OFFICE.

SAMUEL J. RICE, OF LOMA, NORTH DAKOTA.

BAG FILLING AND TYING APPARATUS.

1,072,775.

Specification of Letters Patent.

Patented Sept. 9, 1913.

Application filed February 8, 1912. Serial No. 676,246.

To all whom it may concern:

Be it known that I, SAMUEL J. RICE, a citizen of the United States, residing at Loma, in the county of Cavalier, State of North Dakota, have invented certain new and useful Improvements in Bag Filling and Tying Apparatus; and I do hereby declare the following to be a full, clear, and exact description of the invention, such as will enable others skilled in the art to which it appertains to make and use the same.

This invention relates to bag filling and tying apparatus and particularly to a type adapted for use in handling grain.

The object of the invention resides in the provision of a bag filling and tying apparatus of the character referred to in which the bag tying device remains inactive during the filling of the bag and is automatically thrown into operation when a given weight of material has been supplied to said bag.

A further object of the invention resides in the provision of means whereby the operation of the bag tying device of the apparatus will serve to render the filling device inactive during such operation, said filling device automatically returning to an active state upon the completion of each operation of the bag tying device.

A still further object of the invention resides in the provision of a bag filling and tying apparatus which includes certain improved and novel constructions as will hereinafter appear.

With the above and other objects in view, the invention consists in the details of construction and in the arrangement and combination of parts to be hereinafter more fully described and particularly pointed out in the appended claims.

In describing the invention in detail, reference will be had to the accompanying drawings wherein like characters of reference denote corresponding parts in the several views, and in which—

Figure 1 is a vertical longitudinal section through a bag filling and tying apparatus constructed in accordance with the invention, Fig. 2, a section on the line 2—2 of Fig. 1 showing the parts of the apparatus in full lines in the position they would occupy when the plunger of the bag tying device is retracted, and in dotted lines in the position they would occupy when the plunger of the bag tying device is fully

advanced, Fig. 3, a plan view of one end of the apparatus with the bag tying device removed to more clearly disclose the remaining parts, Fig. 4, a view similar to Fig. 3 partly in section and with certain portions of the apparatus omitted to more clearly disclose the bag tying device, said device being shown with the plunger elements thereof in retracted position, Fig. 5, a view similar to Fig. 4, with the plunger elements of the bag tying device in advance position, Fig. 6, a side elevation of what is shown in Fig. 4, Fig. 7, a detail view looking at the sides of a fragment of the plunger element of the bag tying device and showing the wire twisting means active, Fig. 8, a view similar to Fig. 7 showing the wire twisting means inactive and the parts thereof in the position they would occupy at the termination of the advance stroke of the plunger element of the bag tying device, Fig. 9, a detail view of the wire severing means with the parts thereof shown in inactive position, Fig. 10, a view similar to Fig. 9 with the parts of the wire severing means shown active, Fig. 11, a detail perspective view of one of the bag holding clips of the bag carrier of the apparatus, Fig. 12, partial sections through the bag carrier showing one of the bag holding clips in securing position and in release position, Fig. 13, a section on the line 13—13 of Fig. 9, and Fig. 14, a section on the line 14—14 of Fig. 3.

Referring to the drawings the apparatus is shown as comprising a supporting base A which carries a trough like body A' including parallel spaced side members 20 and 21, a bottom B and an end member 22 connecting the side members 20 and 21 together at their upper ends. The bottom B is formed of a fixed section 23 and a movable section 24, said movable section being disposed at the same end of the side members 20 and 21 as the cross member 22. Pivotedly mounted on each of the side members 20 and 21 is a lever 25 and these levers each support at one end a hanger 26 suitably secured to the adjacent side of the movable bottom section 24. Each lever 25 has adjustably mounted on its end remote from the hanger 26 a balancing weight 27 which is adapted to normally hold the lever in position to dispose the movable bottom section 24 in alignment with the fixed bottom section 23. The extreme outer end of the bottom section 23

is inclined downwardly as at 28 and this inclined portion extends beyond the adjacent ends of the side members 20 and 21. Suitably journaled on the outer side of the side members 20 and 21 respectively at the ends thereof remote from the cross member 22 are corresponding vertical shafts 29. These shafts project above the upper edge of the side members 20 and 21 and have 5 fixed on their upper ends respectively, for rotation therewith, sprocket wheels 30. Suitably journaled on the outer sides of the side members 20 and 21 respectively at the ends thereof adjacent the cross member 22 are corresponding vertical shafts 31 which also project above the upper edge of the side members 20 and 21 and have fixed on their upper ends respectively for rotation therewith sprocket wheels 32. Traveling on each 10 pair of sprocket wheels 30 and 32 which are supported by respective shafts 29 and 31 journaled on the same side member 20 or 21 is a sprocket chain 33. Certain corresponding links of each of the sprocket chains are 15 provided with inwardly directed studs 34 which are encircled respectively by the coiled portions 35 of U-shaped spring members 36, the arms of which members are directed outwardly of the chain 33 and engage over a 20 bag securing clip C. Each of the clips C is formed with a bag engaging portion 37 disposed outwardly of the chain 33 and a reduced neck 38 bent U-shape and embracing the upper edge of the chain 33. This free 25 end of the reduced neck 38 extends inwardly of the chain 33 at an angle to the latter so as to be engaged by one of the sprocket wheels 30 or 32, as the case may be, during the travel of said sprocket chain. The 30 spring member 36 is adapted to normally force the bag engaging portion 37 of the clip toward the adjacent link of the chain 33 so that a bag, indicated at D, may be clamped between said portion 37 and the adjacent 35 chain link and said bag thus secured to the chain 33 for travel therewith. During the operation of the apparatus the bags B are secured successively to the chains 33 by means of the clips C at the end of the apparatus 40 adjacent the shafts 29. As the bags are moved toward the opposite end of the apparatus through the instrumentality of the chains 33 the free ends of the reduced necks 38 of the clips C will successively engage 45 the sprocket wheels 32 and be forced toward the adjacent chain link. This movement of the reduced neck 38 will cause the bag engaging portion 37 of the clip to move outwardly and thus release the bag D previously engaged thereby. This status of the clip C will continue until the reduced neck 38 has passed out of engagement with the sprocket wheel 32 when the spring member 36 will automatically operate to draw the 50 bag engaging portion 37 inwardly against

the adjacent link of the sprocket chain and at the same time move the free end of the reduced neck 38 away from said link. This operation of the clip C will also take place when the reduced neck 38 of same moves 70 into engagement with the sprocket wheel 30, with the result that the empty bags may be secured to the chains 33 without manually operating the clips C.

Suitably supported adjacent the side member 21 is an endless elevator 39 having a discharge mouth 40 directed toward the side member 21. This elevator 39 is supplied with grain by means of a conveyer screw 41 leading from a suitable grain supply and operated through the instrumentality of an engine (not shown) connected to the shaft 42 of said conveyer screw. This shaft 42 is extended through the casing of the elevator 39 and has fixed on the portion thereof disposed within the casing of said elevator the drive sprocket 43 of the elevator. Fixed on the extension of the shaft 42 which is disposed without the casing of the elevator is a beveled gear 43' 90 fixed on a shaft 45 suitably journaled beneath the bottom B and disposed transversely of the latter. One end of the shaft 45 extends beyond the outer face of the side member 20 and fixed on this end of said shaft for rotation therewith is a beveled gear 46. Suitably journaled in the base A and in a journal bracket 47 secured against the outer face of the side member 20 is a vertical shaft 48 which has slidably and non-rotatably mounted thereon a sleeve 49 having fixed thereto a gear 50 adapted to be brought into and out of mesh with the gear 46 by the movement of the sleeve 49 longitudinally of the shaft 48 as will hereinafter appear. Journaled in suitable brackets secured to the inner faces of the side members 20 and 21 respectively are vertical shafts 51 which are disposed in a vertical 100 plane passing through the shafts 31 and through the side members 20 and 21 at right angles to the latter. Fixed on each of the shafts 51 are spaced gears 52, the gears 52 on one of said shafts 51 meshing respectively with the corresponding gear 52 on the other shaft 51. The lower end of the shaft 51 mounted on the side member 20 has fixed thereon a beveled gear 53 which meshes with a beveled gear 54 fixed on the inner end of a shaft 55 journaled in the side member 20 and extending transversely of the latter. Fixed on the outer end of the shaft 55 is a beveled gear 56 which meshes with a beveled gear 57 fixed on a shaft 58 suitably journaled upon the outer face of the side member 20 and extending longitudinally of the latter. Also fixed on the shaft 58 is a beveled gear 59 which meshes with a beveled gear 60 fixed upon the shaft 48 beneath the 110

115

120

125

130

bearing 47. Each of the shafts 51 have fixed on their upper ends sprocket wheels 61 disposed in horizontal alignment with sprocket wheels 62 fixed on respective shafts 31. Traveling on adjacent sprocket wheels 61 and 62 are sprocket chains 63 through the instrumentality of which the rotation of the shafts 51 is imparted to the shafts 31. The discharge mouth 40 of the elevator 39 supports a vertically movable spout 64, the outer end of which is directed downwardly and tapers from each side inwardly as at 65 so as to form a wedge for forcing open the mouth of the bag D disposed in filling relation thereto as the free end of said spout is lowered. The length of this spout 64 is such that when the free end thereof is lowered it will be disposed in correct position to effect the filling of the bag therebeneath with grain delivered thereto from the elevator 39. The upper side of the spout 64 is provided with an opening 66 through which extends a gate 67 supported by a bracket 68 secured to the outer face of the side member 21. The lower edge of this gate 67, when the spout 64 is in its lowermost position, is disposed in such relation to the bottom of the spout as to permit of a maximum flow of grain through the latter. However, as the outer end of the spout is elevated the lower edge of the gate 67 approaches the bottom of the spout 64 so as to constantly decrease the flow of grain and eventually entirely stop such flow by closing the passage of the spout.

Mounted upon the outer face of the side member 20 is a bracket 69 which is provided with an arm 70 disposed between the inner and outer ends of the bracket and directed longitudinally of the side members 20 and 21. Journaled in the outer end of the arm 70 is a shaft 71 disposed transversely of the side members 20 and 21 and having fixed on its inner end a beveled gear 72 which meshes with a beveled gear 73 fixed on the upper end of the shaft 48. Fixed on the outer end of the shaft 71 is another beveled gear 74 which meshes with a beveled gear 75 fixed on a shaft 76 journaled in the outer end of the bracket 69 and disposed longitudinally of the side members 20 and 21. Also fixed on the shaft 76 between the brackets 69 and the shafts 31 is a pitman wheel 77 for a purpose that will presently appear.

Mounted upon the outer face of the side member 20 between the pitman wheel 77 and the shaft 31 is a bracket 78 which supports a base plate 79 disposed at right angles to the side member 20. Slidably mounted upon the base plate 79 is a plunger 80 having a longitudinal passage 81 therethrough. Rotatably supported on the extreme outer end of the base plate 79 is a spool 82 which carries a supply of wire 83. This wire is directed from the spool 82 through the passage 81 and thence across the side members 20 and 21 just inwardly of the shafts 51 so as to be engaged by the bags D as they are moved toward the cross member 22 by the chains 33. Mounted upon the plunger 80 and plate 79 is a plurality of spring controlled dogs 84, and those dogs carried by the plunger are adapted to engage the wire 83 disposed in the passage 81 as said plunger advances across the side members 20 and 21, and thus draw the wire 83 from the spool 82. When the plunger 80 is retracted however, the dogs 84 carried thereby will slide freely over the wire 83 and leave the end of the latter disposed across the side members 20 and 21 just inward of the shaft 51. Formed on the inner end of the upper face of the base plate 79 at the side of the plunger adjacent the pitman wheel 77 is a rack 85. Journaled on the side of the plunger 80 adjacent the pitman wheel 77 and extending longitudinally of said plunger is a shaft 87 having fixed on its inner and outer ends respectively beveled gears 88 and 89. Journaled transversely in the plunger 80 at the inner end of the shaft 87 is a shaft 90 which has fixed on the end thereof adjacent the shaft 87 a beveled gear 91 in mesh with the beveled gear 88. Fixed on the end of the shaft 90 remote from the shaft 87 is a forked wire gripper 92. Journaled transversely of the plunger 80 at the outer end of the shaft 87 is another shaft 93 which has fixed on the end thereof adjacent the shaft 87 a beveled gear 94 in mesh with the gear 89 of the shaft 87. The shaft 93 is extended beyond the gear 94 toward the pitman wheel 77 and fixed on this extension is a gear wheel 95 adapted to mesh with the rack 85 during the reciprocation of the plunger 80 to effect the rotation of the shaft 93 and in turn the rotation of the shafts 87 and 90. Formed on the upper face of the base plate 79 just outward of the rack 85 is a longitudinally directed rib 96 which is interrupted between the ends of the rack 85. The portion of the shaft 93 which is disposed over the rib 96 is provided with a flat face 97 adapted to engage the upper face of the rib 96 during the reciprocation of the plunger 80. It will of course be apparent that such engagement between the rib 96 is interrupted between the ends of the rack 85 and it will be apparent that when the gear 95 moves into engagement with the rack 85 the shaft 93 will pass out of engagement with the rib 96 and thereby leave said shaft free to rotate. The parts heretofore described are so arranged that when the plunger 80 is retracted and the shaft 93 in engagement with the rib 96 the wire gripping member 92 will be positioned with its arms disposed toward the advanced end of the plunger 80 and longitudinally thereof so as to receive the wire 83 therebetween during the ad-

vancing movement of the plunger and before the gear 95 has passed into engagement with the rack 85.

The side face of the pitman wheel 77 which is disposed adjacent the bracket 69 is provided along its peripheral edge with a rib 98 which is interrupted between the ends of a segmental gear 99 also formed on the same face of the pitman wheel 77 and disposed just inward of the rib 98. Journaled in the side member 20 and projecting outwardly therefrom is a shaft 100 which has fixed thereon a knife 101 adapted during the rotation of said shaft to move across the advance end of the plunger 80 and sever the wire 83. Fixed on the outer end of the shaft 100 in position to engage the segmental gear 99 during the rotation of the pitman wheel 77 is a gear 102. This shaft 100 between the knife 101 and the gear 102 is provided with a flat space 103 adapted to engage the upper face of the rib 98 when the gear 102 is out of engagement with the gear 99 and thus hold the shaft 100 against rotation. When the shaft 100 is in engagement with the rib 98 the knife 101 will be disposed vertically above the shaft and the engagement of the gear 102 with the gear 98 during each rotation of the pitman wheel 77 will serve to effect one complete rotation of the shaft 100.

Mounted on the inner face of the cross member 22 is a member E which is adapted to receive and retain the upper end of a filled bag during the tying operation. This member E includes upper and lower corresponding arms 104 and 105 respectively. Each of these arms terminates at its outer end in a forked portion 106, said forked portions being disposed in vertical alinement.

The plunger 80 is connected to the pitman wheel 77 by means of a pitman 107 so that the rotation of said pitman wheel will effect the reciprocation of said plunger. It will be further noted that the end of the lever 25 which carries the weight 27 is pivotally connected to the upper end of the sleeve 49 whereby the oscillation of the lever 25 will effect a reciprocation of the sleeve 49 longitudinally of the shaft 48 and such reciprocation of said sleeve will move the gear 50 into and out of mesh with the gear 46. When the movable section 24 of the bottom B is disposed in its lowermost position against the influence of the weight 27 the gear 50 will be positioned in mesh with the gear 46, while on the other hand, when the section 24 of the bottom has been moved to its uppermost position under the influence of the weight 27 the gear 50 will be positioned out of mesh with the gear 46.

Assuming that a plurality of bags D are supported respectively by corresponding clips on adjacent sides of the chains 33 and 65 that the bag nearest the cross member 22

is disposed in filling relation to the spout 64, which latter is in lowered position as shown in full lines in Fig. 2, the operation of the apparatus is as follows: The conveyer screw which leads from a suitable grain supply and is operated through connection with a suitable engine, will supply the grain to the elevator 39. This elevator will discharge the grain received thereby into the spout 64 which will in turn deliver same to the bag D disposed in filling relation thereto. During this operation of the conveyer screw and elevator, which is continuous, the shaft 45 will be also rotated continuously through the medium of its connection with the conveyer screw shaft 42. It will be here noted that the weight 27 acting on the lever 25 is sufficient to normally hold the floor section 24 in its uppermost position. However, as soon as sufficient weight of grain has been supplied to the bag D, supported upon said floor section, the influence of the weight 27 will be overcome and said floor section 24 will move downwardly and thereby actuate the lever 25 to elevate the sleeve 49 and move the gear 50 into mesh with the gear 46 so that the shaft 48 partakes of the rotation of the shaft 45. This rotation of the shaft 48 is imparted through the various connections previously described to the shaft 51 carried by the side member 20 and the rotation of this shaft 51 will in turn operate the chains 33 to move the filled bag D into the forked portions 106 of the member E and at the same time move the next empty bag into filling relation with the spout 64. During the movement of the filled bag D into the forked portions 106 the upper end thereof will be gathered by reason of the passage thereof between the meshing gears 52. This movement of the filled bag will also bring the latter into engagement with the wire 83 disposed across the side members 20 and 21 just inward of the shafts 51 and result in said wire being bent into embracing relation with respect to the gathered portion of the filled bag. Simultaneously with this operation the shaft 48 serves to rotate the pitman wheel 77 and the initial rotation of this wheel 77 will slightly retract the plunger 80 and sever the wire 83 at that point. Further rotation of the pitman wheel 77 will move the gear 99 out of engagement with the gear 102 and bring the flat face 103 of the shaft 100 against rotation. This last named movement of the pitman wheel 77 will also institute the advance stroke of the plunger 80 through the medium of the pitman 107. During this advance stroke of the plunger 80 the dogs 84 will serve to draw the wire 83 from the spool 82 as has been previously referred to. As the plunger 80 moves across the side members 20 and 21 just inward of the shaft 100

51 the free ends of the severed length of wire 83 will pass between the arms of the forked wire gripping member 92. Just subsequent to the passage of the wire 83 between the arms of the forked wire gripping member 92 the gear 95 will engage the rack 85 and rotate the shaft 93. This rotation of the shaft 93 through the instrumentality of the various connections heretofore referred to will rotate the shaft 90 and the forked wire gripping member 92, which will result in the ends of the severed wire being twisted tightly upon each other so as to bind the severed length of wire around the gathered portion of the filled bag. At the termination of the advance stroke of the plunger 80 the gear 95 will pass out of engagement with the rack 85 and the flat face 97 of the shaft 93 will engage with the section of the rib 96 adjacent the advance end of the plunger 80 so as to stop the rotation of the forked member 92 when same is disposed in the position shown in Fig. 8. Further rotation of the pitman wheel 77 will then retract the plunger 80 and previous to the engagement of the gear 95 with the rack 85 during such retraction the twisted ends of the severed length of wire will be drawn from between the arms of the forked member 92. During this retraction of the plunger 80 the dogs 84 will slide freely over the wire 83 and a new length of wire will remain disposed across the side members 20 and 21 just inward of the shaft 51 ready for use in the next tying operation. It will of course be apparent that immediately following the tying operation the clips C which support the filled bag will be moved to release position in the manner heretofore referred to and such filled bag will be discharged upon the ground by way of the inclined portion 28 of the bottom section 24. It will be noted that during the advanced stroke of the plunger 64 the outer end of the spout 64 is elevated by means of a flexible connection 108, one end of which is secured to the rear end of the plunger 80 and the other end to the outer end of the spout 64. This connection 108 is trained over a suitable guide so as to facilitate the operation thereof. By thus automatically raising and lowering the free ends of the spout 64 by means of the reciprocation of the plunger 80 it will be apparent that the flow of grain from the spout 64 will be stopped during the movement of a filled bag from and an empty bag into filling relation with respect to said spout. As soon as the filled bag is discharged upon the ground the weight 27 will lift the floor section 24 and move the gear 50 out of mesh with the gear 46 and thus stop the rotation of the shaft 48. When this disengagement of the gears 46 and 50 takes place the pitman wheel 77 shall have made one

complete rotation. As soon as the next bag has been supplied with sufficient weight of material to overcome the weight 27 the cycle of operation heretofore described will be repeated.

76

What is claimed is:

1. In a device of the character described, the combination of a bag tying mechanism, a bag carrier, means for delivering material to a given bag secured to the carrier, and means operated by the weight of a filled bag for actuating said bag tying mechanism and simultaneously operating said bag carrier to place another bag in position to receive material from the material delivering means.

2. In a device of the character described, the combination of a bag tying mechanism, a bag carrier, means for delivering material to a given bag secured to the carrier, means operated by the weight of a filled bag for actuating said bag tying mechanism and simultaneously operating said bag carrier to place another bag in position to receive material from the material delivering means, and means actuated at the termination of said operation of the bag carrier for disconnecting the filled bag therefrom.

3. In a device of the character described, the combination of a bag tying mechanism, a bag carrier, means for delivering material to a given bag secured to the carrier, means for intermittently operating the bag tying mechanism and simultaneously and intermittently operating said bag carrier to remove and dispose successive bags from and into receiving position with respect to the material delivering means, and means operated by the movements of said bag tying mechanism for rendering the material delivering means inactive during the movement of an empty bag to receiving position with the respect to the material delivering means.

4. In a device of the character described, the combination of a bag tying mechanism, a bag carrier, means for delivering material to a given bag secured to the carrier, a movable support for the bag being filled, locking means for holding said support against movement until a predetermined weight of material has been delivered to the bag supported thereby, operating means for simultaneously actuating the bag tying mechanism and the bag carrier, and means operated by the movement of said support for rendering the operating means of the bag tying mechanism and bag carrier active.

5. In a device of the character described, the combination of a bag tying mechanism, a bag carrier, operating means for the bag tying mechanism and bag carrier, means for delivering material to a given bag secured to the carrier, a movable support for the bag being filled, locking means for hold-

130

ing said support against movement until a predetermined weight of material has been delivered to the bag supported thereby, a continuously driven element, and means 5 operated by the movement of said support under the influence of the weight of a bag supported thereby for connecting the operating means of the bag tying mechanism and bag carrier with said continuously driven 10 element.

6. In a device of the character described, the combination of a bag tying mechanism, a bag carrier, operating means for the bag tying mechanism and bag carrier, means 15 for delivering material to a given bag secured to the carrier, a movable support for the bag being filled, means for normally holding said support against movement until a predetermined weight of material 20 has been delivered to the bag supported thereby, a rotatable driven shaft, connections between said driven shaft and the operating means of the bag tying mechanism and bag carrier, a gear rotatable with and 25 movable longitudinally of said driven shaft, a drive shaft, a gear fixed on said drive shaft in position to be engaged by the gear on the driven shaft, and connections between the gear on the driven shaft and said 30 movable support normally holding the gear on the driven shaft out of mesh with the gear on the driving shaft and adapted dur-

ing the movement of said support under the influence of the weight of a bag supported thereby to move the gear on the 35 driven shaft into mesh with the gear on the driving shaft.

7. In a bag tying apparatus, the combination of a bag holder, a plunger having a passage therethrough, means for reciprocating said plunger across the bag holder, a wire supply having its strand extending through the passage in said plunger and across the bag holder whereby the free end of said strand will be bent by the application of a bag to the holder into embracing 40 relation with respect to the bag, means for severing the bent portion of the strand prior to the advance stroke of the plunger, dogs carried by the plunger and adapted to engage the strand during the advanced stroke of said plunger to draw the strand from the supply, and means carried by the plunger automatically actuated during the advanced stroke of the latter for twisting the 45 free ends of the severed strand upon each other.

In testimony whereof, I affix my signature, in presence of two witnesses.
